UNITED STATES PATENT OFFICE

ETHEL PARSONS, OF NEW YORK, N. Y., ASSIGNOR TO THE STEARNS & FOSTER COMPANY, OF LOCKLAND, OHIO, A CORPORATION OF OHIO

DESIGN FOR TEXTILE FABRIC

Application filed July 24, 1929. Serial No. 32,182. Term of patent 3½ years.

To all whom it may concern:

Be it known that I, ETHEL PARSONS, a citizen of the United States, residing at New York, in the county of New York and State of New York, have invented a new, original, and ornamental Design for Textile Fabric, of which the following is a specification, reference being had to the accompanying drawing, forming part thereof.

In the drawing:—

The figure is a plan view of a piece of textile fabric, showing my new design, a unit of the design being substantially outlined by indicating arrows, the unit of the design being repeated in the relation indicated by the extension beyond the unit-indicating lines.

I claim:—

The ornamental design for textile fabric substantially as shown and described.

ETHEL PARSONS.
